ELECTRIC PLUG

Edwin William Bonson, London, England

Application July 3, 1936, Serial No. 88,807
In Great Britain July 12, 1935

1 Claim. (Cl. 173—363)

In connecting plugs with insulating caps for wireless apparatus and other purposes, I use a metal part in any suitable conformation but form the insulating body, cap or handle-part in two pieces, these being provided with male and female threads respectively so that when the metal part with the usual connecting wire attached thereto is passed into the one piece of the cap or body suitably formed with a slot or angular recess to retain the metal part, the other piece of the cap is screwed to it for purpose of binding the wire tightly to the metal plug and together provide the required insulating medium.

10 The metal part, the other piece of the cap is screwed to it for purpose of binding the wire tightly to the metal plug and together provide the required insulating medium.

15 The invention is illustrated in the accompanying drawing in which:

Figure 1 is a side elevation of the male part of the device. Figure 2 is a similar view of the female part of the device, Figure 3 is a vertical section taken on the line 1—1 of Figure 1, Figure 20 4 is a plan of Fig. 1, Figure 5 is a similar view to Figure 3 taken at right angles thereto, Figure 6 is a vertical section of the female part of the device, Figure 7 is a form of metal plug suitable for use with the device, Figure 8 is a vertical section of the complete device assembled and showing the plug in position, the cable being omitted, Figure 9 is a similar view to Figure 1 illustrating a modification in the construction of the device illustrated thereon, Figure 10 is a similar view to Figure 2 modified to coact with the device shown in Fig. 9, Figure 11 is a plan of Fig. 10, Figure 12 is an elevation of a modified form of plug, Figure 13 is a plan thereof, and Figure 14 represents a sectional view of the modified device assembled, the plug being shown in elevation.

Referring to the drawing, the insulating body, in accordance with the invention, is constructed in two body parts, the one or top part *a* illustrated in Fig. 1 having a male screw thread whilst the other part *e* shown in Figure 2 is provided with a female screw thread that is internally threaded, so as to interengage or co-act with said part *a*. The parts *a* and *b* of the insulating body are provided with a bore therethrough whilst the section of the bore in the part *a* is furnished with recesses *b* bordering or on each side of said bore as shown in Figures 3 and 5.

50 It will be understood that the insulating plug

made in two parts *a*, *e* are screw threaded to inter-engage with each other and one or other of these parts may be externally milled for ease in dismantling or fitting together; the portion *a* or *j* is centrally perforated with lateral recesses *b*, 5 the portion *e* being perforated in its shell and formed with an enlarged bore to accommodate the metal plug in such a manner that it is held immovably in position when the two parts *a*, *e* are screwed together. One part of the plug body 10 can turn freely on the metal plug without turning the latter.

The metal plug may consist as in Fig. 4 of a suitably shaped piece of metal as *f* perforated at its upper portion to receive the end of the wire 15 or cable *g* which is twisted on itself and, when the two parts *a*, *e* or *j*, *k* are screwed home, will be forced tight on the widened upper part of such plug, as shown in Fig. 8.

In Figs. 9 to 14 is illustrated a modification 20 in which the body part *j* is provided with an internal or female screw thread and the body part *k* is provided with an external or male screw thread and is adapted to interengage or screw into the part *k* as will be readily understood.

In the construction shown in Figs. 12 and 13 the plug is formed with a hexagonal top *m* perforated to receive the wire *g* which is flattened thereon when the two parts *j*, *k* are tightened together.

The hexagonal head may be slotted at *p* to receive the wire *g* and the perforation in part *k* may be hexagonal to receive the plug portion *m*.

I claim:—

An electric plug coupling comprising an insulated body consisting of a male and female interengaging screw threaded part, a vertical axial perforation in each of said parts, two oppositely disposed lateral recesses adjacent one end of the axial perforation in the male part, said recesses 40 being closed at their inner ends, an enlarged bore in the female part in axial alignment with the axial perforation thereof, a metal plug protruding through the latter perforation, said metal plug having a widened centre part located in the 45 enlarged bore aforesaid and terminating in a head held in the lateral recesses of the male part to prevent rotation thereof when the female part is screwed home.

EDWIN WILLIAM BONSON. 50
